205,700

COMBINED COMB AND HAIR TONIC HOLDER THEREIN

Homer M. Hare, Jr., 3836 Don Julio Blvd.,
North Highlands, Calif.

Filed Dec. 1, 1964, Ser. No. 82,860

Term of patent 14 years

(Cl. D86—8)

FIG. 1

FIG. 2

FIG. 3

FIG. 4

FIG. 5

FIG. 6

FIG. 1 is a top edge view of a combined comb and hair tonic holder therein showing my new design;

FIG. 2 is a side elevational view thereof;

FIG. 3 is a bottom edge view thereof;

FIG. 4 is an end elevational view as seen from the left of FIG. 2;

FIG. 5 is an end elevational view as seen from the right of FIG. 2; and

FIG. 6 is a perspective view of the side opposite that shown in FIG. 2.

I claim:

The ornamental design for a combined comb and hair tonic holder therein, as shown.
